UNITED STATES PATENT OFFICE.

BYRON P. LYNDS, OF SANDWICH, ILLINOIS.

DRAW-BAR FOR HARROWS.

SPECIFICATION forming part of Letters Patent No 790,444, dated May 23, 1905.

Application filed February 9, 1905. Serial No. 244,936.

To all whom it may concern:

Be it known that I, BYRON P. LYNDS, a citizen of the United States, residing at Sandwich, in the county of DeKalb and State of Illinois, have invented certain new and useful Improvements in Draw-Bars for Harrows; and I do declare the following to be a full, clear, and exact description of the invention, such as will enable others skilled in the

art to which it appertains to make and use the same.

My invention is an improved draw-bar for sectional harrows adapted to be folded to reduce length, so that it may readily pass between the posts of a gate and may also be readily drawn on narrow roads and lanes when the harrow is folded; and it consists in the construction, combination, and arrangement of devices hereinafter described and

claimed.

In the accompanying drawings, Figure 1 is a top plan view of a folding harrow draw-bar embodying my improvements, showing the same extended, the front ends of the harrow-section connected to the various portions of the draw-bar being indicated in dotted lines. Fig. 2 is a side elevation of the same, showing one of the draw-bar sections folded on the intermediate section; and Fig. 3 is a detail perspective view showing one of the joints between the members or sections of the draw-bar.

My improved draw-bar is here shown as adapted for use in connection with a four-section harrow, and comprises an intermediate section 1 and end sections 2. On the front and rear sides of the intermediate section and end sections, at the contiguous ends thereof, are plates 3 4, which are bolted thereto and are provided at their inner upper corners with upwardly-projecting lugs 5 6, which are respectively recessed on their inner and outer sides, as at 7 8. Said recesses 7 8 form shoulders 9 10 on the upper sides of the said lugs, and shoulders 11 are formed on the under sides of the said lugs at the contiguous ends of the plates 3 4 and flush with the contiguous ends of the intermediate and end sec-

tions of the draw-bar. The lugs of the plates are disposed in overlapping relation, and the lugs of the respective plates are connected together by a pivot-bolt 12, whereby the end and intermediate sections of the draw-bar are hinged or pivotally connected together to enable the end sections to be folded over the intermediate section or to be extended therefrom.

When the end sections are folded over the intermediate section, the lugs 5 6, respectively, engage the shoulders 10 9 and coact with the pivot-bolt 12 to support and maintain the end sections above and spaced from the intermediate section and substantially parallel with relation thereto to prevent the devices which are employed for connecting the harrow-sections to the sections of the draw-bar from coming in contact with one another. When the end sections are extended from and in line with the intermediate section, as when the harrow-sections are disposed in position for operation, the shoulders 11 of the plates 3 4 are in mutual contact and serve, in connection with the pivot-bolt 12, to keep the end sections and the intermediate section in a common horizontal plane. It will be observed that the pivot-bolts or pins 12 are directly above the joints between the intermediate and end sections and that the plates 3 4 are bolted to the front and rear sides of the intermediate and end sections and serve not only to act as hinges between the said sections, but also, by reason of the overlapping relation of their respective lugs or ears, to act as braces between the intermediate and end sections, so as to prevent the end sections from becoming angularly disposed backwardly from and with relation to the intermediate section and to also relieve the pivot-bolts or braces 12 of undue lateral stress.

To the center of the intermediate section is pivotally connected a clevis 13, which extends forwardly therefrom. One of the bolts 14 which secure each pair of the plates 3 to one end of the intermediate section is provided at its front end with an eye 14.

Link-rods 15 have their outer ends hooked to the eyes of the bolts and their inner ends connected to a ring 16, to which the double-tree may be connected in the usual manner.

5 A link 17 connects the said ring and the clevis 13. It will be observed that by thus connecting some of the draw-links to some of the bolts which secure the hinge-plates to the intermediate section the draft stress is 10 applied to the hinge-plates on the rear side of the intermediate section and is caused to counteract the stress exerted on the said hinge-plates by the drag of the end sections of the draw-bar.

15 It will be understood that when the harrow is at work and the sections thereof are disposed side by side the end sections of the draw-bar will be extended from the intermediate section thereof and that when it is necessary to draw the harrow through a gateway or other narrow place the outer harrow-sections will be folded over the intermediate section, and the ends of the draw-bar will be folded over the intermediate section thereof.

20 25 From the foregoing description, taken in connection with the accompanying drawings, the construction and operation of the invention will be readily understood without requiring a more extended explanation.

30 Various changes in the form, proportion, and the minor details of construction may be resorted to without departing from the principle or sacrificing any of the advantages of this invention.

35 Having thus described my invention, what

I claim as new, and desire to secure by Letters Patent, is—

1. A harrow draw-bar comprising a plurality of sections disposed end to end, plates on the front and rear sides of the said sections at the contiguous ends thereof and formed with overlapping, upwardly-extended ears, and laterally and oppositely extending shoulders, for the purpose set forth, and a pivot connecting the said ears of the respective hinge-plates and disposed above the joints between the draw-bar sections, substantially as described. 40 45

2. A sectional foldable draw-bar for harrows, comprising an intermediate section, 50 end sections, hinge connections between the intermediate and end sections and including plates to bear against the front and rear sides of said sections, bolts securing said hinge-plates to the said sections, certain of 55 the bolts which secure certain of the said plates to the intermediate section having eyes at their front ends, and draft-links connected to the eyes of the said bolts, to apply draft stress to the hinge-plates on the rear 60 side of the intermediate section, for the purpose set forth.

In testimony whereof I have hereunto set my hand in presence of two subscribing witnesses.

BYRON P. LYNDS.
